Application April 20, 1935, Serial No. 17,534
In Belgium April 27, 1934

13 Claims. (Cl. 103—113)

The present invention relates to devices for producing a suction and it is more especially, although not exclusively, concerned with devices of this kind serving to the priming of liquid pumps driven by an internal combustion engine, for instance an explosion engine.

The object of the present invention is to provide a device of this kind which is better adapted to meet the requirements of practice than devices used for the same purpose up to the present time.

The essential feature of the present invention consists in utilizing an internal combustion engine the intake of which can be connected, at will, either with the atmosphere, or with the chamber in which it is desired to create the suction, in such manner that, the engine being started, it is allowed to gather speed, air for the fuel mixture being sucked in from the atmosphere, after which the air intake is connected with said chamber whereby the engine, while slowing down, sucks in the air present in said chamber.

Other features of the present invention will result from the following detailed description of some specific embodiments thereof.

Preferred embodiments of the present invention will be hereinafter described, with reference to the accompanying drawings, given merely by way of example, and in which:

Fig. 1 is a diagrammatical view of a motor pump unit provided with the device according to the present invention;

Figs. 2, 3 and 4 are diagrammatic views showing, on an enlarged scale, various embodiments of the device according to the present invention, respectively;

Fig. 5 is a view, similar to Fig. 1, showing an arrangement, according to the present invention, for the suction of liquids.

It will first be assumed that, being given a motor-pump unit including a pump 1, of any kind whatever (for instance of the centrifugal type, as it will be supposed in the following description) driven by an explosion engine 2 (Fig. 1), it is desired to create a suction adapted to permit the priming of pump 1.

According to the present invention, this engine 2 is arranged in such manner that its air intake pipe 3 can be connected, at will, either with the atmosphere or with a chamber in which it is desired to create the suction, that is to say, in the present instance, the delivery pipe 4 of pump 1, ahead of a valve 5, which will be kept closed during the period of priming.

For this purpose, air intake pipe 3 is connected, before the carburetor 6, with a casing forming a chamber 7 which is provided, on the one hand, with an orifice 8 of dimensions sufficient for permitting the inflow of the whole of the air necessary for feeding the engine, and, on the other hand, with an orifice 9 which is connected, through a suitable conduit, with said delivery pipe 4.

These orifices 8 and 9 are provided with suitable stopping means 13.

It will be readily understood that, if orifice 8 is opened, the engine is capable of working in a normal manner.

It can thus be started and allowed to gather speed.

If, when the engine is running at a high speed of revolution, orifice 8 is closed and orifice 9 is opened, the engine, the power of which decreases but which keeps running under the effect of its fly-wheel, sucks in the air present in chamber 7, in the delivery pipe 4 of the pump, in the pump itself, and also in its suction pipe 10.

After a certain number of revolutions, the speed of the engine shall have decreased and said engine will tend to stop.

It will then suffice, if the vacuum thus obtained in the suction pipe 10 is not sufficient, to close orifice 9 and then immediately to open orifice 8, owing to which the engine will again gather speed.

By repeating this operation a sufficient number of times, if necessary, it will be possible to obtain a suction such that the priming of the pump takes place.

Advantageously, the arrangement just above described will be completed by the provision of means adapted to prevent the liquid from rising as far as chamber 7 under the effect of the suction of the engine.

For instance this result will be obtained by means of a device including a float 11, disposed in a chamber 12, and so devised that it permits air to flow past it to chamber 7 but that, as soon as the level of the liquid becomes too high in chamber 12, said float is moved upwardly and cuts off the communication between said chamber 12 and chamber 7.

Of course the various elements of the combination above described may be given any suitable specific form.

Concerning first the means for stopping orifices 8 and 9, it will be advantageous to make use, among other embodiments, of those illustrated by Figs. 2 to 4.

- According to the first of these embodiments, shown by Fig. 2, there is provided a three way cock structure provided with a control member 13 capable of occupying any of three different positions.
- 5 In the first position of this member 13, which is the position shown in Fig. 2, orifice 8 is in communication with intake pipe 3 and orifice 9 is stopped.
- 10 In the second position, or intermediate position, both of the orifices 8 and 9 are stopped.
- 15 In the third position, orifice 9 is in communication with air intake pipe 3 and orifice 8 is stopped.
- 20 Owing to this arrangement, by switching control member 13 from one of its extreme positions to the other one, it is possible to obtain the operation above described. Furthermore, owing to the existence of the intermediate position, orifices 8 and 9 are never short-circuited, that is to say both orifices are never opened simultaneously, so that the suction already created in pipe 4 will be maintained irrespectively of the position of control member 13.
- 25 According to the second embodiment, which is shown by Fig. 3, orifice 8' is provided with a valve 14, which can, for instance be operated manually, said valve being subjected to the action of a spring 15 which tends to close it.
- 30 The other orifice, 9', is provided with an automatic valve, or check valve 16, subjected to the action of a spring 17 which tends to close the valve which opens, when the engine is running, under the effect of the suction exerted by the 35 engine as soon as valve 14 is closed, spring 17 being of less strength than spring 15.
- Finally, in the third of these embodiments, which is shown by Fig. 4, there is provided also a valve 14' adapted to coact with orifice 8'' and 40 subjected to the action of a spring 15', and a valve 16', subjected to the action of a spring 17' and arranged to cooperate with orifice 9''.
- 45 But, in this embodiment, these two valves are operatively connected together in such manner that the operation that tends to open valve 14' has necessarily caused, previously, the closing of valve 16', and that the operation intended to close valve 14' necessarily produces the opening of valve 16', but only after said valve 14' has 50 been closed.
- For this purpose, for instance, both of these 55 valves 14' and 16' are mounted in a sliding manner on a common rod 18, which is preferably subjected to the action of a return spring 18'.
- A spring 17' is interposed between valve 16' and a collar 19 carried by one of the ends (for instance the lower end) of rod 18.
- 60 A spring 15' is interposed between valve 14' and a stationary stop.
- Rod 18 is provided with a collar 20 adapted to lift valve 14' from its seat after said rod 18 has moved, in the suitable direction, a distance sufficient for causing valve 16' to be applied against its seat.
- 65 Finally, rod 18 is provided with another collar or flange 21 adapted to move valve 16' away from its seat after said rod 18 has moved, in a direction opposite to that above mentioned, a distance sufficient in order that valve 14' may 70 be applied against its seat.
- It will be readily understood that, whatever be the embodiment that is chosen, whatever be the direction in which the control member is actuated, orifices 8 and 9 are never opened simultaneously since, even in the case of the sec-
- ond of the embodiments just above described, valve 16 closes as soon as valve 14 opens.
- Concerning now the float device, it may be made in any of the following manners:
- In the very simple embodiment shown in Fig. 2, this device includes a ball 11, made of a material lighter than the liquid, said ball being enclosed in chamber 12 and being adapted to stop an orifice 22 in communication with orifice 9 as soon as the liquid rises in chamber 12 up to a predetermined level.
- Alternately, as shown in Fig. 3, the float member 11' is mounted on a rod 23, suitably guided, and the upper end of which is adapted to raise, when the float member is moved upwardly, the rod 24 of a valve 25 (preferably fitted with a rubber lining) which is then applied upwardly against a seat 26.
- Of course, the different operations necessary for obtaining the working of the device as above described can be effected manually, for instance by turning control member 13 (Fig. 2) or by actuating a handle 29 (Fig. 3) adapted to push down the stem of valve 14, or a handle 27 (Fig. 4) suitably connected with rod 18, said handle 27 being advantageously provided with a pawl 28 operative to keep valve 14' open during normal working of the engine.
- Means may be provided for automatically switching from one mode of working to the other as the engine speed reaches predetermined limits. Such an arrangement is shown, for example, in Fig. 3 in which a lever 29 is adapted to act on the stem of valve 14, against the action of spring 15.
- A centrifugal governor 30, driven by the engine, is provided with a sleeve 31 which is moved upwardly, against the action of a spring 32, the higher as the engine runs faster.
- This sleeve 31 is provided with a collar or flange 33 adapted to push downwardly the free end of lever 29 when the speed of revolution of the engine drops below the predetermined minimum, which produces the opening of valve 14.
- A pawl 34 is adapted to keep lever 29 in its lowered position, said pawl being rigid with a finger 35.
- Sleeve 31 is provided with a second collar 36 adapted to push in an upward direction the free end of said finger 35 when the speed of revolution of the engine exceeds the predetermined maximum, which brings pawl 34 out of action, thus releasing lever 29 and permitting valve 14 to close under the action of its spring 15.
- It will be readily understood that such an automatic mechanism might be combined with any other device for alternately closing orifices 8' and 9'.
- It should be noted that the pressure in air intake pipe 3 will vary very much according as to which of the orifices 8 and 9 (or 8' and 9', or 8'' and 9'') is connected with said intake pipe.
- Consequently, in order to reduce to a minimum the perturbation produced in the carbureting system of the engine by these variations of pressure, it is advantageous to provide means for balancing the pressures acting on the various elements of this system.
- For instance, in the case of a carburetor including a float chamber 37 (the carburetor as such not being shown as it is located behind chamber 37), there is provided a conduit 38 connecting said float chamber, which otherwise will be made fluidtight, with intake pipe 3 (or chamber 7). Thus the variations of pressure produced

ahead of the carburetor will not influence the rate of feed of fuel.

Fig. 5 concerns the case in which only an internal combustion engine 2, for instance an explosion engine is available and it is desired to create in a vessel 39 a suction or vacuum for sucking into said vessel a body, for instance of pasty consistency, or a liquid containing impurities (such for instance as muck-water or water laden with sand).

In this case the engine is fitted with a casing forming a chamber 7 such as that above described, and a conduit 40 is provided for connecting the orifice 9 of this chamber 7 (as shown in Fig. 2, or 9' or 9'' of chamber 7' or 7'' of Figs. 3 and 4, respectively) with vessel 39, a float device being of course interposed if necessary.

With such an arrangement, by proceeding as above described in detail, it will be possible to fill up vessel 39, even if the volume of this vessel is relatively great (for instance several cubic meters).

In order to empty vessel 39 when it is full, there may be provided a suitable pipe 41, provided with a valve 42 or the like.

In order to prevent the liquid sucked in through inlet pipe 43 from flowing out through said pipe 43 when valve 42 is opened, said inlet pipe 43 may be prolonged upwardly so that it opens into the upper part of vessel 39. Or said pipe 43 might also be provided with a valve 44.

It is believed that the preceding description of the different embodiments of the device according to the present invention and the explanations given with reference thereto are sufficient for making it unnecessary to describe the working of these embodiments.

Of course, it is to be understood that the engine utilized in connection with the present invention may be of the two-stroke type, in which case the working of the device will be particularly satisfactory if this engine is fitted with a scavenging pump. On the other hand the engine might be of the fuel injection type and, more generally of any kind whatever, provided it is an internal combustion engine.

In a general manner, while the above description discloses what is deemed to be the practical and efficient embodiments of the present invention, it should be well understood that it is not desired to be limited thereto as there might be changes made in the arrangement, disposition and form of the parts without departing from the principle of the present invention as comprehended within the scope of the appended claims.

What is claimed is:

1. A device for producing a suction in a vessel comprising, in combination, an internal combustion engine having at least one cylinder, means for connecting the interior of said cylinder selectively with the atmosphere or with the inside of said vessel, and means for feeding fuel to said engine continuously even when the vessel is connected to said cylinder.

2. A device for producing a suction in a vessel comprising, in combination, an internal combustion engine having at least one cylinder, a chamber communicating with the inside of said cylinder, said chamber having two orifices communicating respectively with the atmosphere and with said vessel, means for opening and closing said orifices selectively so that one of said orifices is in open position when the other is closed, and means for feeding fuel to said engine con-

tinuously and regardless of which orifices are open or closed.

3. In a device according to claim 2, said means for feeding fuel including a carburetor and a float chamber, and means for connecting the inside of said float chamber with the inside of said first mentioned chamber whereby the pressures in said two chambers will be balanced.

4. A device according to claim 2 in which said chamber has the shape of a body of revolution, said operating and closing means including a rotating control member within said chamber provided with at least one hole and adapted to register with one or the other of said orifices.

5. A device for producing a suction in a vessel in connection with an internal combustion engine having at least one cylinder and a carburetor connected to the inside of said cylinder comprising, in combination, a chamber adapted to communicate with said carburetor, said chamber having two orifices communicating respectively with the atmosphere and with said vessel, means for selectively opening and closing said orifices so that one of said orifices is in open position when the other is closed.

6. A device for producing a suction in a centrifugal pump for priming the same, in combination with a combustion engine having at least one cylinder, means for connecting the inside of said cylinder selectively with the atmosphere or with the interior of said pump, the inside of said cylinder being shut off from the atmosphere when connected to said pump and being shut off from said pump when connected to the atmosphere, and means for feeding fuel to said engine continuously even when the cylinder is connected with the interior of said pump.

7. A device according to claim 2 in which the first mentioned means of said claim include valves adapted to cooperate with said orifices, springs for yieldingly maintaining said valves in their closed positions, and control means for forcing the valve that cooperates with the first mentioned orifice into the open position.

8. A device according to claim 2 in which the first mentioned means of said claim include two valves adapted to cooperate with said orifices respectively, two springs for yieldingly maintaining said valves in their closed positions respectively, and means for controlling said valves in such manner that the valve adapted to cooperate with the first mentioned orifice can be opened only after the other valve has been closed, and the closing of the first mentioned valve is necessarily followed by the opening of the other valve.

9. A device according to claim 2 in which the first mentioned means of said claim include a first valve adapted to cooperate with the first mentioned orifice, a spring interposed between a stationary part of the device and said valve for urging it toward its closed position, a second valve coaxial with the first mentioned one adapted to cooperate with the second mentioned orifice, a rod slidable in both of said valves, means for operating said rod, a spring interposed between a part of said rod and the second valve for urging it toward its closed position, and collars carried by said rod and adapted to cooperate with said valves respectively, said collars being so positioned that the first valve can be opened only after the second valve has been closed and the closing of the first valve is necessarily followed by the opening of the second valve.

10. A device according to claim 2 further in-

cluding means for preventing liquid to reach said chamber.

11. A device according to claim 2 further including means for automatically closing the first orifice and opening the second one when the speed of the engine reaches a predetermined maximum value and opening the first orifice and closing the second one when the speed of the engine reaches a predetermined minimum value, said automatic means being operative by the engine.

12. A device for producing a suction in a vessel comprising, in combination, an internal combustion engine having a plurality of cylinders and a plurality of intake passages connected to the inside of said cylinders, a chamber, a connection between said chamber and the intake passages leading to some only of said cylinders, said chamber having two orifices communicating respectively with the atmosphere and with said vessel, means for opening and closing said ori-

fices selectively so that one of said orifices is in open position when the other is closed, and means for feeding fuel to said engine continuously.

13. A device for producing a suction in a vessel comprising, in combination, an internal combustion engine having at least one cylinder, means for connecting the interior of said cylinder selectively with the atmosphere or with the inside of said vessel, said means comprising two orifices communicating respectively with the atmosphere and with said vessel, and means for automatically closing the first orifice and opening the second one when the speed of the engine reaches a predetermined maximum value and, opening the first orifice and closing the second one when the speed of the engine reaches a predetermined minimum value, said automatic means being operative by the engine.
